This technical drawing illustrates a double door assembly. The doors are shown in an open position, revealing a central partition. The outer frame is labeled with the number 12. The top horizontal bar is labeled 10. The lower horizontal bar is labeled 13. The central vertical partition is labeled 9. The left door is labeled 15, and the right door is labeled 14. Numerous other components are labeled with numbers 1 through 19, including 1, 2, 3, 4, 5, 6, 7, 8, 10, 11, 12, 13, 14, 15, 16, 17, 18, and 19, which likely represent different parts like panels, seals, or hardware.

CABIN

John J. Wilson, Oneida, N. Y.

Application April 16, 1935, Serial No. 16,672

1 Claim.

(Cl. 20—2)

This invention relates to cabins, and has for the primary object the provision of a portable device which will be easy to assemble or take apart and may be conveniently carried or stored in a small space and when assembled will exclude weather elements and provide variable ventilation and light to the interior thereof and may only be disassembled from the interior thereof.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a perspective view illustrating a cabin constructed in accordance with my invention.

Figure 2 is a vertical sectional view illustrating the same.

Figure 3 is a transverse sectional view illustrating the device.

Figure 4 is a perspective view illustrating one of the gables of the cabin.

Figure 5 is a perspective view illustrating one of the end walls of the cabin.

Figure 6 is a perspective view illustrating one of the sections of a side wall.

Figure 7 is a perspective view, partly in section, illustrating one of the sections of the floor of the cabin.

Figure 8 is a perspective view illustrating a fastener.

Referring in detail to the drawings, the numeral 1 indicates a knock-down cabin wherein the roof 2 thereof is constructed from any suitable fabric. The cabin includes end walls 3, side walls 4 and gables 5 mounted on and removably secured to the end walls and each of substantially triangular shape and provided with a notch 6 to receive a beam 7 for supporting the roof 2.

One of the end walls 3 is provided with a window opening 8 which may be closed by any well-known type of window, while the other end wall is provided with a doorway 9 which also may be closed by any suitable type of door. The side walls 4 are partly of solid formation and partly of open structure to provide additional ventilation and sunlight when needed. The open structure of the side walls is closed by flaps 10 forming an integral part of the roof. Fasteners 11, as shown in Figure 8, are employed to secure

the flaps 10 to the side walls and also employed to secure flaps 12 to the gables, the flaps 12 being formed integrally with the roof 2. The flaps 10 may extend to overlie a portion of the end walls and be secured in place by removable cleats 13.

The side walls 4 each consists of a pair of sections bolted or otherwise secured together, as shown at 14. The solid portions of the sections are of panel construction reinforced by beams 15. The side and end walls rest upon flooring 16 and are bolted or otherwise secured thereto, as shown at 17. The flooring is made up of sections and which sections are reinforced by beams 18 adapted to rest upon the ground or a suitable foundation.

The end walls are of panel formation and are reinforced by beams 19. The beams of the end and side walls provide substantially rectangular-shaped frames and the uppermost beams of the side walls form rests or seats for the gables which are bolted or otherwise secured thereto. The gables are also of panel construction reinforced by beams 20. The fasteners referred to are all arranged upon the interior of the cabin 21 making it impossible to take the cabin apart from the exterior thereof. The interior of the cabin may be ventilated by raising the flaps 10, and further ventilated by raising a part of the roof. Additional ventilation, of course, may be had 30 through the doorway 9 and window 8.

A cabin of the character described will be comparatively light in weight, easy to handle when disassembled and convenient to assemble and will provide variable ventilation and also admit 35 sunlight as desired.

Having described the invention, I claim:

A cabin comprising a sectional flooring, sectional side and end walls supported by said flooring, said side walls having elongated ventilating 40 openings located in the upper portions thereof and gable portions supported by said end walls, a member supported by the gable portions, fabric roofing supported by the member, flaps formed on said roofing to open and close the ventilating 45 openings of the side walls, flaps formed on the roofing and engaging the gable portions, fasteners detachably securing the flaps to the side walls and the gable portions, and fasteners detachably securing the side and end walls together and to the flooring and the gable portions 50 to the end walls and located within the walls and gable portions.

JOHN J. WILSON.
